HAIR CURLER

Nathan L. Solomon, Mount Vernon, N. Y.

Application December 2, 1937, Serial No. 177,666

6 Claims. (Cl. 132—41)

The present invention is concerned with the art of curling hair and especially is directed to an improved and simplified curler, the objects, advantages, and features of which will be better understood from the following detailed description considered in the light of the accompanying drawing in which:

Fig. 1 is a side view of the hair curler according to my invention.

Fig. 2 is a horizontal and transverse sectional view taken on the line 2—2 of Fig. 1.

Fig. 3 is an exploded view of the hair curler shown in Figs. 1 and 2.

Illustrative of the embodiments disclosed, the hair curler H includes a perforated tube T, a perforated cover C, a loop L, and a compressible stay S.

As shown cover C is provided with depending lugs 4 having perforations 5 adapted to be lined up with perforations 6 of tube T when the cover is superimposed and mounted on the tube.

The cover and tube are swingably mounted on inwardly directed overlapped ends broadly designated 7 of the one piece wire loop L having sides 8 thereof adapted to widely straddle the tube and cover and including a brace 9 rotatably supporting the relatively soft rubber disc 10 constituting a stay having a peripheral rim or surface provided with a closed band of spaced teeth 11.

More particularly each end 7 is integrally merged with curved corner portions or ribs 12 each defining a groove or trough 14 having inclined sloping means 15 whereby the overlapping inner terminals of the contacting ends 7 are offset in respect to the bases of ribs 12.

In assembling the curler, the cover is mounted on the tube, and stay S is threaded onto the brace 9. Thereafter the arms 8 are separated sufficiently to thread terminals of ends 7 into aligned openings 5 and 6 of the cover and tube. Subsequently arms 8 are allowed to move towards each other to permit terminals 7 to approach each other.

During this operation sloping parts 15 of beads or ribs 12 pass through the aligned openings 5 and 6 in the sides of the tube and cover. Consequently these parts are disposed in the concavities or notches of beads 12 as shown in Fig. 2 and from an examination of the latter it will be appreciated that beads 12 interlock both the tube and cover however permitting both of the latter to swing relative to each other with the bases of beads 12 serving as fulcrum means while the inclined sides of the beads prevent displacement of the tube and cover longitudinally of the ends 7.

In fact terminals 7 after beads 12 are interlocked with the cover and tube cannot be accidentally moved away from each other since the inclined parts 15 constitute stop means cooperating with the diametrically disposed portions of the tube and cover to prevent such separation. In a word, it may be stated that after ends 7 have been threaded into the tube and cover, the terminals if moved towards each other snap into interlocking relation with both the tube and cover to straddle adjacent walls thereof although the latter serve as bearing means permitting the loop to be rotated or swung.

Having assembled the curler, hair is interposed between the tube and cover to be clamped. Subsequently the curler is rotated about its long axis to wind a plurality of convolutions of hair. Thereafter the loop is swung to a closing position in which case the resilient disc or wheel is yieldingly pressed over the forward end of the tube to clear the latter to be in part received within the bore thereof as illustrated in Fig. 1. With the stay interlocked with the tube, sides 8 of the loop hold the hair wound about the tube and cover in place.

The teeth 11 of the stay define grooves which receive the forward part of the tube thus preventing accidental rotational displacement of the stay and consequently after wheel 10 is in part within the tube it is held in a desired stayed relation and the roughened or corrugated surface of the wheel also constitutes means to prevent slippage of the wheel when grasped by the fingers of the operator in shifting the stay to its locking or unlocking position.

As many changes could be made in the above construction and many widely different species or structural embodiments could be devised without departing from the scope thereof, it is intended that all matter hereinbefore described in the specification and illustrated in the accompanying drawing shall be interpreted as illustrative and not in a limiting sense.

45 I claim:

1. In a hair curler, a tube, a cover mounted on said tube, a resilient loop comprising arms spaced from the sides of said tube and cover and including ends disposed substantially normal to said arms, beaded means integral with said ends and arms and adapted to straddle adjacent parts of said tube and cover and constituting means to prevent shifting of said tube and cover longitudinally of said ends, and a compressible resilient disc rotatably mounted on said loop and having

a toothed rim adapted to disengageably interlock with one end of said tube.

2. In a hair curler, a tube, a cover mounted on said tube, a resilient loop comprising arms spaced from the sides of said tube and cover and including offset ends disposed substantially normal to said arms, beaded means integral with said ends and arms and adapted to movably but closely straddle adjacent parts of said tube and cover and constituting means to prevent shifting of said tube and cover longitudinally of said ends, and a compressible resilient disc rotatably mounted on said loop and having a toothed rim adapted to disengageably interlock with one end of said tube, said toothed rim having grooves adapted to receive a terminal portion of said tube to prevent rotation of said disc during interlocking relation of the latter with said tube.

3. A roller for contacting with an end of a hair curler to secure clamp means thereof in hair clamping position, the periphery of the roller

having circumferentially spaced tooth like projections defined by pairs of outwardly converging wall portions.

4. A roller for pivotal mounting and coacting with an end of a hair curler to secure clamp means thereof in hair clamping position, the roller being resilient and having a tooth like periphery.

5. In a curler, tubular means about which hair is adapted to be wrapped, a clamping bail carried by said means, and a clamping roller mounted on the bail to clip into engagement with an end of the tubular means, said roller having a roughened peripheral surface.

6. In a curler, tubular means about which hair is adapted to be wrapped, a resulting clamping bail carried by said means, and a resilient roller mounted pivotally on the bail to clip into engagement with an end of said tubular means, said roller having a corrugated periphery.

NATHAN L. SOLOMON.
